CONTAINER FOR PHONOGRAPH NEEDLES AND THE LIKE

Carl Pfanziehl, Highland Park, Ill., assignor to
Pfanziehl Chemical Company, a corporation of
Illinois

Application May 1, 1941, Serial No. 391,395

6 Claims. (Cl. 206—46)

This invention relates to a container for phonograph needles or similar small objects.

It has heretofore been the practice to package phonograph needles either in paper envelopes or in large cardboard backs. Packages of this type do not pack well and the needles are likely to be torn loose. Furthermore the packages are not attractive.

The present package affords a clear view from all sides of the needle, has no projecting portions, may readily be packed for shipment or mailed in an ordinary envelope, and provides an attractive display. At the same time the needle is sealed against dirt and moisture and cannot be dislodged, lost or stolen without removing the entire package. Furthermore the package provides for the use of a gasket which may be used for ornamentation or advertising purposes.

The invention is illustrated in the drawing in which Fig. 1 is a plan view of the container with a needle within it; Fig. 2 is a side elevation thereof; Fig. 3 is a section taken along the line 3 in Fig. 1; Fig. 4 is a view corresponding to Fig. 1 of the lower half of the container; Fig. 5 is a plan view of the gasket; and Fig. 6 is a view of the underside of the top half of the container.

As shown in the drawing, the container 10 is split to provide a bottom portion 11 and a cover portion 12, each of which is made from a transparent, thermoplastic, non-frangible material. It is preferred to use a resinous material such as the methyl methacrylate resins, or a styrene composition. The bottom portion 11, while molded integrally, may be considered as comprising a bottom plate 13 provided with an upstanding peripheral flange 14 which provides an abutment 15 at its upper edge, which supports a paper gasket 16. Correspondingly, the cover portion 12 may be considered as formed from a cover plate 17 provided with a down-turned peripheral flange 18, likewise provided with an abutment 19 at its lower edge.

Interlock means are provided on top and bottom. It is preferred to have at least two sets of interlocks. In the form here shown, the bottom portion of the container is provided with a pair of pins 20 and the cover portion with a pair of complementary cavities 21. The pins are placed upon the studs 22 and the cavities are formed in studs or ears 23. Obviously other forms of interlock means may be employed and the relative positioning of the male and female members may be reversed or the cover may be provided with one male and one female element 55

and the bottom with complementary interlock portions.

Confining means are provided within the container for holding the needle or other elongated small object. In its preferred form this confining device consists of an integral upstanding split casket 25. In its simplest form the casket is formed in two equal sections, the lower half 25a being integrally formed with the bottom portion of the container, and the upper half 25b being formed integrally with the cover of the container. The interior 26 of the casket is only slightly larger than the needle it is to contain. The entire container including casket is integrally formed from a transparent, thermoplastic, non-frangible material. The gasket 16 is preferably a fibrous sheet provided with a central opening 27 slightly smaller than the casket, and side slots 28 of a size sufficient to admit the pins 20. The gasket may readily be provided with ornamentation or advertising to accentuate the needle or other material within the casket, and the top or bottom portion thereof may readily be provided with printed matter, giving directions for opening of the container, and installation and use of the needle.

The bottom and cover portions of the container may be secured together by the use of a small amount of solvent in the cavities 21 or upon the pins 20, but it is much more satisfactory to fuse a small portion of the pin after assembly of the container. This may be accomplished by the insertion of a hot needle through the wall of the container into the pin. This leaves a very small punctured area where the needle has been withdrawn and produces a small area of cloudiness around it which does not detract from the attractiveness of the container.

This method has the further advantage that a package so prepared is practically non-refillable. Once it has been opened the package cannot be again sealed without there being obvious and clear evidence of the tampering. Also, the cover and bottom portions are thin enough so that the act of prying them apart, once sealed, slightly warps them, and the package cannot even be closed tightly thereafter.

The foregoing detailed description has been given for clearness of understanding only, and no unnecessary limitations should be understood therefrom.

What I claim as new, and desire to secure by Letters Patent, is:

1. A package for elongated small objects comprising a relatively large thin transparent non-

frangible bottom portion, a relatively small central cavity therein of substantially the size of the elongated object to be contained therein, a transparent thin non-frangible thermoplastic cover, a central cavity in the cover corresponding to the central cavity in the bottom portion, and means for positioning cover and bottom portions to bring the corresponding cavities into alignment.

2. A package as set forth in claim 1, in which an ornamented gasket substantially divides the cover and bottom portions except for the central cavity.

3. A container comprising a thin flat base provided with an integral upstanding peripheral flange, a thin flat cover having a downwardly directed peripheral flange adapted to abut on the upstanding flange of the base, and an elongated centrally located integral split casket having complementary portions integrally formed from the base and cover, the cover and base portions being of transparent non-frangible thermoplastic material.

4. A container as set forth in claim 3, in which the base and cover portions are provided with integral interlock means.

5. A transparent thermoplastic container com-

prising top and bottom portions, the top and bottom being provided with at least two sets of integral complementary interlock means, each set of interlock means including a male and female member, and the male member of each interlock means being partially fused to the corresponding female member of the interlock means, and there being a small punctured area associated with each set of interlocking means extending to the periphery of the container.

6. A container comprising a thin flat disk base portion provided with an integral upstanding circumferential flange, at least two studs adjacent the flange, a thin flat disk cover portion having a downwardly directed circumferential flange adapted to abut on the upstanding flange of the base and provided with studs complementary to and adapted to abut upon the studs of the base portion, the studs being provided with complementary male and female interlock members, the base and cover being composed substantially entirely of transparent thermoplastic non-frangible material, and an elongated centrally located integral split casket having complementary portions integrally formed from the base and cover.

CARL PFANSTIEHL.
